ERNEST ARTHUR JACKSON, OF CHORLTON-CUM-HARDY, MANCHESTER, ENGLAND, AS
SIGNOR TO KAY AND LEE LIMITED, OF MANCHESTER, ENGLAND, A BRITISH COM-
PANY

TROUSERS, KNICKERBOCKERS AND SUCH LIKE

Application filed May 14, 1929, Serial No. 362,970, and in Great Britain July 26, 1928.

My improvements relate to trousers, plus-fours, knickerbockers, and such like apparel for male wear.

The usual manner of suspending or supporting such garments is by braces, belts, strap pieces with buckle, or such like.

My improvements concern a method of suspending such garments by an encased encircling band which is slidable or partly slideable in a fabric sheath or casing applied in the locality of the waist band, either outside or inside, but preferably inside the waist band so as not to interfere with the outside appearance of the garment. The encircling band is broad and flat and of an elastic nature or is partly elastic, or is combined with some elastic medium which is so applied or so fastened or adjusted (by button-holes or fastener engagement with button) as to cause the waist band to cling to the trunk when the proper buttoning or fastening has been effected. As a consequence when the trousers are worn they are securely and comfortably supported from the trunk by an encased encircling band but in an accommodating and an adjustable fashion. The power of adjustment and the elasticity makes for ready fitting and comfort.

Also, braces, belts etc., are dispensed with, together with belt loops, side straps, etc., and outside buttons are done away with, so that on the outside of the waist band there are no protruding elements.

The accompanying drawings illustrate trouser and like suspending means made in accordance with my improvements.

In the said drawings:

Fig. 1 is a diagram showing a pair of trousers with one form of the improved suspending means applied thereto and fastened up.

Fig. 2 shows a broken view looking at the inside front of the waistband, the strap being shown in fastened position in dotted lines and unfastened in full lines.

Fig. 3 is a view similar to Fig. 1 but with the improved fastening means undone.

Fig. 4 is a broken view inside the back portion and clearly shows the sheath or casing.

Fig. 5 is a fragmentary perspective view

illustrating on a larger scale the construction of the sheath.

Fig. 6 illustrates the sheathed and mainly elastic band detached.

Fig. 7 is a diagram plan showing the fastening undone. 55

Fig. 8 indicates the use of a detachable fastener which combines with buttons to effect adjustment of the elastic band.

Fig. 9 is a diagram showing a modified fastening scheme. 60

In the practical carrying out of my improvements and according to the scheme outlined above, I apply to or in juxtaposition to the waist-band *a* of the trousers *a* a sheath or casing, which is completely closed at one end and provided with a single aperture at its opposite end. This sheath or casing is preferably almost continuous and may be either outside or inside, but it is preferably arranged inside and may be of strong lining fabric as indicated in Figs. 1, 3 and 5, or it may be of the material of the trousers turned over at its top edge, as indicated in Figs. 2, 4 and 8. In the drawings, I show a sheath or casing *b* of strong fabric which is secured by lines of sewing at *b'*, *b'*. In this sheath or casing *b*, and so as to be nicely guided thereby, I insert a webbing *c* of elastic, either wholly elastic or in part, and this is anchored as to one end by lines of stitching at *c'*, but the stitching may be in the middle as well, to provide two elastic lengths. The arrangement of stitching the end *c'* is the one preferred by me. 70

To the free end of the webbing of elastic *c* I attach a fabric or other strap *c2* with a sequence of button holes *c3*.

If both ends of the webbing of elastic emerge from a sheath or casing I should have a button-receiving end and button holes on the strap part, but, as stated, an arrangement such as illustrated is the one preferred and for tightening-up to make the trousers grip the body one of the sequence of button-holes *c3* is engaged with a provided button *a2* sewn right through onto the elastic webbing *c*. 90

The wearer gets into the trousers with ease when undone, and after buttoning up the 95 100

fly he simply draws the free or strap end c_2 of the elastic band sufficiently tight and buttons the proper button hole c_3 onto the button a_2 , whereupon the waist band will be found to fit perfectly and to comfortably cling to the trunk to properly suspend the trousers.

Instead of a sequence of button holes c_3 I may have a fastener d of the known type on the strap portion c^{2x} and arrange for this to engage one of several provided buttons a_3 , a_3 , as Fig. 8 suggests.

The webbing may be continuous elastic webbing which is the kind I am using, or the webbing may have an elastic insertion or insertions, or webbing with spring devices inter-connecting lengths of same may be used.

It is anticipated the scheme will be very suitable for juvenile knickerbockers etc., as also for sports suits, a good and accommodating fit at the waist being assured together with greater comfort and freedom when bending or exercising.

25 That portion of the garment on which the fly-closing buttons are sewn is termed herein the button stand, while that portion which carries the button holes adapted to cooperate with said buttons is termed the button-hole stand. In the drawings, the said button stand is designated f and the button-hole stand f' .

If desired, and as indicated by Fig. 9, I may have two buttons a_4 , a_5 , one behind and one in front of the button stand, these two buttons a_4 and a_5 being stitched together. The elastic webbing e could be drawn-up to the desired degree and the appropriate button hole c_3 could be engaged with button a_4 . This means the elastic webbing is slightly stretched and pre-engaged at a_4 , and so, to secure the waist band around the body, a wearer only requires to engage top button hole e in the front fly section with button a_5 , the remaining elasticity in webbing e permitting this. The elastic waist band is thus completely engaged.

I declare that what I claim is:

1. In a garment of the trousers type provided with a fly opening having a button stand and a button-hole stand cooperating to close said opening, the combination of a waist band, a completely enveloping sheath carried by the waist band and having a single aperture adjacent the button stand of the "fly", a resilient band stitched as to one end in the sheath and adjacent the button-hole stand of the "fly", said resilient band being entirely located within the sheath, and having a non-resilient strap portion attached to its free end and emerging at the single aperture adjacent the button stand of the fly, said non-resilient strap portion having a plurality of button-holes, connected front and rear buttons attached to the top of the button stand of the fly, the emerging end of the non-re-

silient strap portion being adapted to engage the rear button and the upper end of the button-hole stand of the "fly" being adapted to engage the front button.

2. In a garment of the trousers type provided with a fly opening having a button stand and a button-hole stand cooperating to close said opening, the combination of a waist band, a sheath carried by said waist band, said sheath being completely closed as to one end and having a single aperture adjacent the button stand of the "fly" of the garment, a resilient band located in the sheath and permanently stitched thereto adjacent the button-hole stand of the "fly", a non-resilient strap portion attached to the resilient band and emerging at the single aperture adjacent the button stand, said non-resilient strap portion having a plurality of button holes, a button carried by the waist band adjacent the button-hole stand of the "fly" for engagement with one of the button holes in said non-resilient strap portion for anchoring the latter, and means for securing the top of the "fly" in closed position.

In testimony whereof I have signed my name to this specification:

ERNEST ARTHUR JACKSON.
